UNITED STATES PATENT OFFICE.

SAMUEL W. COOPER, OF McCAULLEY, TEXAS.

COMBINED WRITING-DESK AND FILE-CABINET.

1,128,415.

Specification of Letters Patent. Patented Feb. 16, 1915.

Application filed May 13, 1913. Serial No. 767,408.

To all whom it may concern:

Be it known that I, SAMUEL W. COOPER, a citizen of the United States, residing at McCaulley, in the county of Fisher and State of Texas, have invented certain new and useful Improvements in Combined Writing-Desks and File-Cabinets, of which the following is a specification.

This invention relates to combined writing desks and file cabinets, and has as its object to provide an article of this class so constructed that it may be ordinarily used as a writing desk and that the file cabinet may be conveniently moved into position to permit of inspection of the files contained therein.

Another aim of the invention is to provide in a combined desk and file cabinet, means for mounting the file cabinet in such manner that it will not interfere with the pigeon-hole structure of the desk as ordinarily arranged and will be entirely out of the way while the desk is being used for ordinary writing and clerical purposes.

Another aim of the invention is to so construct the file cabinet that it will contain a maximum number of files in a relatively small space and will ordinarily be housed in the top and back of the desk and will be so mounted that it will be unnecessary for the user to move his chair away from the desk in order to gain access to the cabinet.

For a full understanding of the invention reference is to be had to the following description and accompanying drawing, in which:—

Figure 1 is a perspective view showing my improved cabinet arranged within a desk having a conventional form of sliding top, said sliding top, however, being omitted in order to better illustrate the position of the cabinet. Fig. 2 is a vertical front to rear sectional view illustrating the arrangement of the cabinet and the desk, the pigeon-hole structure being however, omitted, for the sake of clearness. Fig. 3 is a perspective view of one end of the cabinet, the same being removed from the desk. Fig. 4 is a perspective view of one of the clips arranged within each compartment of the cabinet.

Corresponding and like parts are referred to in the following description and indicated in all the views of the drawing by the same reference characters.

In the drawing the desk is indicated in general by the reference numeral 1 and the table, or writing top thereof is indicated at 2. The true top of the desk includes as usual sides 3 and a top board 4 which connects the said sides and the said top further includes a back 5 which in this instance is curved so as to support the top piece 4 forwardly of the back of the desk body.

The ordinary pigeon-hole arrangement is indicated at 6 and is located beneath the top 4, although the structure as a whole is spaced below the said top to accommodate the file cabinet, which will now be described.

The cabinet embodying the present invention includes a bottom 7 which is curved from front to rear, preferably on the arc of a circle and which is of a width to extend between the sides 3 of the desk top. The bottom is supported by the side-pieces 8 which are of segmental form and the arcuate edges of which define the upper edges of the sides of the compartments which constitute the interior of the cabinet, as will be presently explained. It will be observed that the arcuate edges of the segmental side-pieces 8 are concentric to the curved back 5 of the desk top so that the cabinet may occupy a minimum amount of space when in position beneath the top. The side-pieces 8 at their apices are pivoted as at 9 to the sides 3 of the desk top at a point concentric to the curved back 5. The cabinet further includes a front 10 which extends the entire length thereof and is secured to the side-pieces 8 and this front is provided with a knob or finger-piece 11 which may be grasped for the purpose of swinging the cabinet upon its pivot 9 into and out of position for use. The cabinet further includes a back 12 which is also secured to the side-pieces 8. The interior of the cabinet is divided transversely by partitions 13 and from front to rear by partitions 14, thereby forming compartments 15 which are to contain the files to be stored within the cabinet.

In order to retain the files in their proper compartments clips are provided and each of the clips is preferably formed from a single length of resilient wire bent intermediate of its ends to provide a connecting portion 16 and a finger-piece 17, the wire at each end of the connecting portion being positioned as at 18 and thence coiled as at 19 and extended to form attaching pieces

20 which are secured by means of staples or other suitable fastening devices 21 to the rear wall of each compartment 15, the convex sides of the bowed portions 18 being
 5 presented toward the bottom of the respective compartment. It will be apparent from inspection of Fig. 2 of the drawings that these clips may be readily raised so as to permit of the introduction and removal of
 10 files from any of the compartments and that ordinarily they will hold the files compactly and prevent them being drawn out when the cabinet is swung into and out of position for use. Also, by reference to Figs. 1 and
 15 2 it will be observed that the user of the device wishing to inspect a file, may pull forwardly on the knob 11, the cabinet being in position housed within the top of the desk, until the front of the cabinet rests
 20 upon the table 2, in which position all of the compartments of the cabinet will be in plain view of the user and in position to permit of ready removal or introduction of files.
 25 In order to protect the files contained within the compartments 13 from dust and dirt and in order that the cabinet may be closed when it is swung to position for use, there is provided a pivoted top including
 30 substantially triangular sides 22 and a connecting top member 23 which latter, is curved from front to rear to conform to the curvature of the body of the filing cabinet.
 35 By reference to Fig. 2 it will be seen that the sides 22 are mounted upon the same pivots as are the sides 8 of the cabinet and consequently the connecting top portion 23 is concentric to the body portion of the cabinet. It will be apparent therefore that the cover 23 may be swung forwardly, the cabinet proper remaining in the position shown in Fig. 2 so as to close the desk or that it may be swung forwardly as stated
 40 45 above to close or cover the compartments of the cabinet when the cabinet is in position for use.
 Having thus described the invention what is claimed as new is:—

50 1. In an article of furniture of the class described, a table having an overhanging top, a relatively fixed cabinet beneath and spaced from the top, a movable cabinet including segmental sides pivoted at their apices, and an arcuate body supported between said sides concentrically to the pivots for the sides, the sides being movable upon their pivots to position the body of the movable cabinet within the space between the fixed cabinet and the top or to position the same in front of the top.

2. In an article of furniture of the class described, a table having an overhanging top, a cabinet including segmental sides pivoted at their apices, a body supported between said sides and having compartments, the sides being movable upon their pivots to position the body within the top or to position same in front of the top, and a cover member including sides mounted upon the pivots for the first-mentioned sides and movable pivotally independent of the said first-mentioned sides, and an arcuate top extending between the said sides of the cover member.

3. In an article of furniture of the class described, a base, a movable cabinet operatively supported by the base, said cabinet being mounted to travel in an arcuate path above the base and an independently shiftable cover for the movable cabinet, said cover being adapted for movement with the cabinet.

4. In an article of furniture of the class described, a base, an overhanging top having sides supported by the base, a fixed cabinet supported by the base, the outer walls of said cabinet being spaced from the sides and the overhanging top, a movable cabinet operatively supported by the base, said movable cabinet being mounted to travel in an arcuate path around the fixed cabinet and between said cabinet and the adjacent walls of the sides and the top, the movable cabinet being shiftable to position beneath the top, or to position in advance of the top, and an independently movable cover for the movable cabinet.

5. In an article of furniture of the class described, a base, a fixed cabinet supported by the base, a movable cabinet operatively supported by the base, said cabinet being mounted to travel in an arcuate path above the base and around the fixed cabinet, and an independently movable cover for the movable cabinet.

6. In an article of furniture of the class described, a base having an overhanging top, a movable cabinet operatively supported by the base, said cabinet being mounted to travel in an arcuate path above the base and being shiftable to position beneath the top or to position in advance of the top, and an independently shiftable cover for the movable cabinet, said cover being adapted for movement with the cabinet.

In testimony whereof I affix my signature in presence of two witnesses.
